UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,258,783.

Specification of Letters Patent. Patented Mar. 12, 1918.

Application filed June 30, 1917. Serial No. 177,916.

To all whom it may concern:

Be it known that I, CHARLES W. KECKLER, a citizen of the United States, residing at Newark, in the county of Essex and State 5 of New Jersey, have invented certain new and useful Improvements in Telephone-Exchange Systems, of which the following is a full, clear, concise, and exact description.

This invention relates to telephone exchange systems, and more particularly to 10 such systems in which connections are established between telephone lines terminating at different switchboards.

In such systems in establishing connections between local and toll lines, it is usual 15 for the local operator when receiving a call for a toll line to connect the calling line with a trunk circuit extending to a recording operator, who then finds out from the calling subscriber, the number or name of the 20 desired party and fills out a toll ticket giving the proper instructions to the toll operator. This ticket is then forwarded to the toll operator, and the recording operator 25 upon disconnecting from the recording trunk circuit, causes a signaling device of the local link circuit to furnish to the originating operator a characteristic signal, commonly known as a peremptory disconnect 30 signal. The local or originating operator thereupon disconnects the link circuit from the recording trunk circuit and the calling line. The connection between the calling 35 local and the wanted toll line is then built up under direction of the toll operator upon receipt of the toll ticket.

Systems of this character heretofore employed have been in connection with local and toll switchboards located in the same 40 office or in separate offices situated near each other. Where the boards are so situated it is economical to employ a three conductor recording trunk circuit between the boards and to control the peremptory disconnecting 45 signal over the third conductor which is separate and distinct from the two conductors forming the talking circuit. However, when the two switchboards are located quite a distance apart, for example, several miles, 50 it is not economical to provide the extra or third conductor for the trunk circuit, and it becomes necessary to use the two talking conductors only and to control the peremptory disconnecting signal over these conductors. Also since a toll connection in-

volves expensive toll lines and equipment, which it is necessary at all times to maintain in good working order, it is desirable to have all control apparatus located at or near the toll board where it can be centralized and 60 be available for use with one or more of several trunk circuits extending to different local switchboards located in different offices. It is, therefore, the object of this invention to provide a system of this character in 65 which the desirable features above set forth are realized.

For a more complete understanding of this invention reference should be had to the 70 following description considered in connection with the accompanying drawing containing one embodiment thereof.

In the drawing there is shown a recording trunk circuit A, extending from a local or originating operator's position of a switchboard X, to a recording operator's desk or switchboard Y. At the local switchboard X, there is a cord circuit B, which may be employed in connecting a calling subscriber's 75 line D with the recording trunk circuit A. At the recording operator's desk Y, there is located a cord circuit C, by means of which the recording operator may answer calls over and connect the telephone set with the recording trunk circuit. 80

Assuming that the operator at the local switchboard X receives a call for a toll line, the plug 3 of the cord circuit B is immediately inserted in the jack 4 of the recording trunk circuit A, whereupon calling supervisory lamps is lighted and relay 6 is 85 operated. When both windings of relay 6 are connected in circuit with the winding of supervisory relay 7, the supervisory relay does not operate, but does operate when the 90 right-hand winding of relay 6 is short-circuited. The operation of relay 6 causes lamp 8 to be lighted over a circuit from battery through the lamp 8, contact 9 of relay 10, contact 11 of relay 12, and the contact 95 of relay 6 to ground. The recording operator observing the lighted condition of the lamp 8, inserts plug 15 of the cord circuit C into jack 16 of the recording trunk circuit A. Relay 10 is thereupon operated over 100 a circuit from battery through resistance 17, sleeve contacts of the plug 15 and the jack 16, and the left-hand winding of relay 10 to ground. Relay 10, in operating, causes 105 the effacement of the lamp 8 and the energ- 110

gization of relay 12. The energizing circuit for relay 12 may be traced from battery through the winding of relay 12, contact 18 of relay 10, and the contact of relay 6 to ground. Relay 12, upon energization, completes a locking circuit for itself through contact 14 thereof and the contact of relay 6. The operation of relay 10 also closes its contact 19, thereby short-circuiting the right-hand winding of relay 6, whereupon the supervisory relay 7 is operated to complete for the calling supervisory lamp 5, a shunt circuit including resistance 20. This lamp is thereby effaced. Relay 12, in operating, removes battery supply from the talking strands 21 and 22 of the trunk circuit. At the time relay 10 is operated, its contact 23 is closed, causing the operation of a slow release relay 24, which, in operating, opens its contact 25, thereby preventing the operation of relay 26 upon the energization of relay 12.

After the recording operator has received all necessary information from the calling subscriber, the plug 15 of the cord circuit C may be withdrawn from the jack 16, whereupon relays 10 and 24 release. Since relay 12 is now locked up, the release of relay 24 causes the operation of relay 26 over a circuit from battery through the winding of relay 24, contact 25 thereof, winding of relay 26, upper alternate contact of relay 12, and the upper winding of the retardation coil 27 to ground. The resistance of relay 26 is such that when in circuit with relay 24, relay 24 does not receive sufficient current to cause it to attract its armature and open its contact 25. The operation of relay 26 opens its normal and closes its alternate contact, whereupon an intermittent energizing circuit for relay 10 is completed from battery through interrupter 30, right-hand winding of relay 10 and the alternate contact of relay 26 to ground. Relay 10 is thereby successively energized and deenergized as long as the alternate contact of relay 26 is closed. This energization and deenergization of relay 10 causes the intermittent closure of its contact 19, whereby through the intermittent short-circuiting of the right-hand winding of relay 6, the flow of current over the talking circuit of the recording trunk circuit is successively increased and decreased. Supervisory relay 7 is therefore successively energized and deenergized and as a result thereof, calling supervisory lamp 5 is intermittently lighted to furnish a peremptory disconnect signal. The local operator upon observing this disconnect signal immediately disconnects the cord circuit B from the calling line and the recording trunk circuit. Upon the withdrawal of the plug 3 from the jack 4, relay 6 releases, thereby opening the locking circuit

of relay 12. Relay 26 then releases, opening the intermittent energizing circuit of relay 10. All apparatus is now restored to normal condition. 65

If, while the cord circuits B and C are connected with the recording trunk circuit A, the local operator desires to attract the attention of the recording operator, the plug 3 is momentarily withdrawn from the jack 4. Upon the withdrawal of the plug 3 from the jack 4, relay 6 releases, thereby opening the locking circuit of relay 12, which releases its armatures, connecting battery to the talking conductors 21 and 22, whereupon relay 31 in the cord circuit C operates to light lamp 32. Upon the reinsertion of the plug 3 in the jack 4, relay 6 operates, establishing an energizing circuit for relay 12, which then attracts its armatures, disconnecting battery from the talking conductors, whereupon the relay 31 releases to extinguish the lamp 32. Each time that the plug 3 is withdrawn from jack 4, the lamp 32 will light, thereby furnishing a recall signal to the recording operator. 70 75 80 85 90

Should the recording operator for any reason desire to attract the attention of the local operator, the momentary withdrawal of the plug 15 from jack 16 will cause the momentary lighting of the lamp 5. This is effected through the release of relay 10 when the plug 15 is withdrawn from jack 16. When relay 10 releases, the short circuit of the right-hand winding of relay 6 is removed, whereupon relay 7 releases, removing the shunt from lamp 5, which thereupon lights. Since relay 24 is slow in releasing, it does not release its armature during the momentary removal of the plug 15 from the jack 16. Upon the reinsertion of the plug 15 into jack 16, relay 10 is again operated, whereupon lamp 5 is effaced in the manner herein described. 95 100 105 110

What is claimed is:

1. In a telephone exchange system, the combination of a trunk circuit extending from a first to a second switchboard, a link circuit at each switchboard connected with the trunk circuit, a signaling device at the first switchboard individual to the link circuit thereat, a source of current connected with the talking circuit, switching mechanism located at the second switchboard rendered effective upon the disconnection of the link circuit thereat from the trunk circuit for intermittently varying the flow of current over the talking circuit, and a relay at the first switchboard responsive thereto for causing the intermittent operation of the signaling device. 115 120 125

2. In a telephone exchange system, the combination of a trunk circuit comprising a two-conductor talking circuit extending from a first to a second switchboard, a link

circuit at each switchboard connected with the trunk circuit, a signaling device at the first switchboard associated with the link circuit thereat, a source of current connected with the talking circuit, switching mechanism located at the second switchboard rendered effective upon the disconnection of the link circuit thereat from the trunk circuit for successively increasing and decreasing the flow of current over the talking circuit, and a relay at the first switchboard responsive thereto for causing the intermittent operation of the signaling device.

3. In a telephone exchange system, the combination of a trunk circuit comprising a two-conductor talking circuit extending from a first to a second switchboard, a link circuit at each switchboard connected with the trunk circuit, a signaling device at the first switchboard associated with the link circuit thereat, a source of current connected with the talking circuit, interrupter mechanism at the second switchboard, a relay responsive to the disconnection of the link circuit at the second switchboard from the trunk circuit for including the interrupter mechanism in operative relation to the talking circuit thereby to increase and decrease successively the flow of current thereover, and a relay at the first switchboard responsive thereto for causing the intermittent operation of the signaling device.

4. In a telephone exchange system, the combination of a trunk circuit comprising a two-conductor talking circuit extending from a first to a second switchboard, a link circuit at each switchboard connected with the trunk circuit, a signaling device at the first switchboard associated with the link circuit thereat, a source of current connected with the talking circuit, a relay at the second switchboard connected in the talking circuit, interrupter mechanism thereat, a relay responsive to the disconnection of the link circuit at the second switchboard from the trunk circuit for causing the interrupter mechanism to intermittently short-circuit a portion of the winding of the first mentioned relay, and a relay at the first switchboard responsive to the resulting increased and decreased flow of current in the talking cir-

cuit for causing the intermittent operation of the signaling device.

5. In a telephone exchange system, the combination of a trunk circuit comprising a two-conductor talking circuit extending from a first to a second switchboard, a link circuit at each switchboard connected with the trunk circuit, a signaling device at the first switchboard associated with the link circuit thereat, a source of current connected with the talking circuit, a pair of relay windings at the second switchboard connected in the talking circuit, interrupter mechanism thereat, a relay responsive to the disconnection of the link circuit at the second switchboard from the trunk circuit for causing the interrupter mechanism to intermittently short-circuit one of the pair of relay windings, and a relay at the first switchboard responsive to the resulting increased and decreased flow of current in the talking circuit for causing the intermittent operation of the signaling device.

6. In a telephone exchange system, the combination of a trunk circuit comprising a two-conductor talking circuit extending from a first to a second switchboard, a link circuit at each switchboard connected with the trunk circuit, a signaling device at the first switchboard associated with the link circuit thereat, a source of current connected with the talking circuit, a relay at the second switchboard responsive to the disconnection of the link circuit thereat from the trunk circuit, interrupter mechanism and a second relay at the second switchboard, an operating circuit for the second relay including the interrupter mechanism completed upon the response of the first relay, a pair of relay windings at the second switchboard connected in the talking circuit, one of which is intermittently short-circuited by the intermittent operation of the second relay, and a relay at the first switchboard responsive to the resulting increased and decreased flow of current in the talking circuit for causing the intermittent operation of the signaling device.

In witness whereof, I hereunto subscribe my name this 27th day of June, A. D., 1917.

CHARLES W. KECKLER.
